(57) CLAIM

The ornamental design for a chandelier, as shown and described.

DESCRIPTION

FIG. 1 is a front and perspective view of a chandelier showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear and perspective view thereof.

The broken lines depict portions of the chandelier in which the design is embodied that form no part of the claimed design.
